(57) **CLAIM**

The ornamental design for scissors handle rings, as shown and described.

DESCRIPTION

FIG. 1 is an isometric view of the scissors handle rings of my new design;

FIG. 2 is a side view thereof;

FIG. 3 is a top view thereof; and,

FIGS. 4 and 5 are opposing end views thereof.

The broken lines shown on the drawings are for illustrative purposes only and form no part of the claimed design.
